UNITED STATES PATENT OFFICE.

AUGUST EMILIANI, OF DUNMORE, AND JOSHUA ROSSINI, OF OLYPHANT, PENNSYLVANIA.

TICKET-HOLDER.

1,368,910.

Specification of Letters Patent. Patented Feb. 15, 1921.

Application filed July 24, 1920. Serial No. 398,669.

To all whom it may concern:

Be it known that we, AUGUST EMILIANI and JOSHUA ROSSINI, a subject of the King of Italy and a citizen of the United States, respectively, residing at Dunmore and Olyphant, respectively, in the county of Lackawanna and State of Pennsylvania, have invented new and useful Improvements in Ticket-Holders, of which the following is a specification.

The object of our present joint invention is the provision of a ticket holder readily operable by an authorized person for the removal of a ticket but calculated to effectively prevent the removal of a ticket and the substitution of another ticket by a mischievous person.

The ticket holder is possessed of a wide range of usefulness being adapted to be employed on mining and freight cars as well as on office doors and the like, and with this in mind the invention consists in the improvement as hereinafter described and definitely claimed.

25 In the accompanying drawings, hereby made a part hereof:—

Figure 1 is a front elevation of our novel ticket holder.

30 Fig. 2 is a vertical central section taken in the plane indicated by the line 2—2 of Fig. 1.

Fig. 3 is an enlarged detail section showing the manner of applying the key through the medium of which the ticket holder is 35 controlled.

Fig. 4 is a detail view taken at right angles to Fig. 2 and hereinafter explicitly referred to.

Similar numerals of reference designate 40 corresponding parts in all of the views of the drawings.

Among other elements our novel ticket holder comprises a casing body 1 having a slot 2 in its body for the deposit of the 45 ticket to be held and also having a chute 3 in registration with the slot. The said chute 3 is formed between a front wall 4 and a false front wall 5, and the lower end of the chute is arranged above an eduction opening 50 6 designed to deliver a ticket to a receiver 7 which is preferably, though not necessarily employed. In the front wall 4 and the false front wall 5 are registered openings 8, and in the lower portion of the front wall 4 is a 55 sight opening 9 through which the inscrip-

tion on the ticket is exhibited. The front wall 4 is further provided below the opening 9 with a notch 10 said notch 10 being formed in the inner side of the front wall. Formed in the top wall of the casing body 1 adjacent to the back wall thereof is an opening 11.

In addition to the casing body 1 characterized as stated, the ticket holder comprises a vertically swinging cover 12, a ticket support 13, a rockable key piece 14, and connections between said rockable key piece and the support 13 as hereinafter set forth. The cover 12 is pivoted at 15, and is provided with a guard arm 16 that works through the 70

before mentioned opening 11. Consequently when the cover 12 is opened for the insertion of a ticket to be exhibited, the guard arm 16 will be swung forwardly through the 75

opening 17 in the false wall 5 so as to intersect the chute 3 and prevent the gravitation of the card or ticket to its exhibition position until the cover 12 is closed. Manifestly this provision is calculated to effectively prevent the surreptitious removal of a ticket or card 80

through the slot 2. Fixed to and extending forwardly from the back wall of the casing body 1 is a spindle 18, arranged in alignment with the openings 8, and on the said spindle is revolubly mounted the rockable 85

key piece 14; said key piece being of angular form in cross section, Figs. 1 and 2, and being designed to be turned by an authorized person through the medium of the key 19 shown in Fig. 3. The rockable key piece 14 90

is provided with a lateral arm 20, Figs. 2 and 4, and said arm 20 is connected, in turn, with a rod 21 the lower end of which is connected to the rear arm of a lever 23 the forward end of which is connected by a link 22 95

with the support 13, Fig. 2. Said support 13 is pivoted at 23* and is normally held in the position shown in Fig. 2 by one or more spring strips 24. As its name imports the support 13 is designed to support the ticket 100

in such position that the inscription on the ticket will be displayed through the opening 9. The said ticket is effectively held against removal by the support 13. When, however, an authorized person wishes to remove the 105 ticket from the holder it is simply necessary for such person to position the key 19 on the key piece 14 and then turn the key about its axis when the support 13 will be swung downwardly and hence will permit the ticket 110

to drop through the slot 6 into the receiver 7 or into the operator's hand placed to receive it. When the key 19 is removed the spring or springs 24 will operate to promptly 5 return the support 13 to its normal position in which position the forward end of the support will rest in the notch 10 so as to break joints with the front wall 4 of the casing body and thereby lessen the liability 10 of unauthorized movement of the support 13 by a person seeking to remove the exhibited ticket in a wrongful manner.

It will be apparent from the foregoing 15 that we have provided a ticket holder which is not unduly expensive and yet may be depended upon to hold and exhibit a ticket or the like in such manner that the ticket cannot be removed and replaced with another ticket by an unauthorized person.

20 Having described our invention, what we claim and desire to secure by Letters-Patent, is:—

1. The combination in a ticket holder of a hollow casing body having a slot in its top 25 wall and an opening in said top wall in rear of said slot and also having a chute communicating with the slot and an opening in the inner wall of the chute, and a cover pivotally connected with the casing body above 30 the top wall thereof in position to normally rest over and guard the slot and having a guard arm arranged to work through the opening in the top wall and to be extended through the opening in the inner chute wall 35 to support a ticket or card dropped through the slot and into the chute.

2. The combination in a ticket holder of a casing body having a chute and aligned 40 openings in the walls of said chute and also having a discharge opening below and in

alignment with the chute, a rockable key-piece arranged in the casing body in alignment with the said openings of the chute walls and having a lateral arm, a spring-pressed support normally maintained with 45 its forward portion between the lower end of the chute and the discharge opening, a lever mounted in the lower portion of the casing body, a connection between one arm of said lever and the ticket support, and a 50 connection between the other arm of the lever and the lateral arm of the rockable key-piece.

3. The combination in a ticket holder, of a casing body having a front wall in which 55 is a display opening and a false front wall between which and the front wall is formed a chute and also having registered openings in the front wall and false front wall and a discharge opening below and in spaced relation to the lower end of the chute, and a recess or notch in the inner side of the front wall below the chute, a spindle fixed to and extending forwardly from the back wall of the casing body in alignment with the registered 60 openings in the front wall and the false front wall, a rockable key-piece on said spindle and having an arm, a spring-pressed ticket support mounted in the casing body, a lever mounted in the lower portion of the 65 casing body and having its forward arm connected with the ticket support, and a rod interposed between and connecting the rear arm of the lever and the arm on the rockable key-piece. 70

75 In testimony whereof we affix our signatures.

AUGUST EMILIANI.
JOSHUA ROSSINI.
